UNITED STATES PATENT OFFICE.

WILLIAM E. BURKS, OF PITTSBURGH, PENNSYLVANIA.

ACCOUNTING FILE OR REGISTER.

1,189,661.

Specification of Letters Patent.

Patented July 4, 1916.

Application filed June 23, 1914. Serial No. 846,854.

To all whom it may concern:

Be it known that I, WILLIAM E. BURKS, citizen of the United States, residing at Pittsburgh, in the county of Allegheny and State of Pennsylvania, have invented certain new and useful Improvements in Accounting Files or Registers, of which the following is a specification.

My invention relates to new and useful improvements in filing cabinets and has particular reference to those of the type employed in filing daily counter sale slips.

The principal object of my invention is to provide a filing cabinet of the type specified, which is simple in construction and may, therefore, be cheaply manufactured and is so designed as regards the construction and general arrangement of the slip receiving drawers that the slips may be quickly inserted in the proper place or removed with equal rapidity.

A further and more specific object of my invention is to provide a cabinet consisting in a plurality of individual slip receiving drawers which may, in number, be equal to the letters of the alphabet so that the sale slips may be easily filed under an alphabetical system.

A still further object of my invention is to mount each individual slip receiving drawer in a retaining plate and to provide each drawer with an automatic catch which, when the drawer is pulled from the retaining plate, will engage co-acting catches formed thereon to permit the drawer to be swung downwardly in dependent horizontal position so that access may be easily had to the various sale slips.

The above recited and other incidental objects of a similar nature, which will be hereinafter more specifically treated, are accomplished by such means as are illustrated in the accompanying drawings, described in the following specification, and then more particularly pointed out in the claims, which are appended hereto and form a part of this application.

With reference to the drawings, wherein there has been illustrated the preferred embodiment of this invention as it is reduced to practice, and throughout the several views of which similar reference numerals designate corresponding parts, Figure 1 is a detail perspective view illustrating one of the slip receiving drawers and retaining plate therefor, this view also showing the catch

member employed in adapting the drawer to be withdrawn from the retaining plate and then swung downwardly in dependent position. Fig. 2 is a plan view of one terminal of the retaining plate shown in Fig. 1 and illustrating particularly the manner in which the catch in Fig. 1 operates; Fig. 3 is a detail perspective view of a drawer and retaining plate, showing a slight modification of the device.

In carrying out my invention, I provide a retaining plate 39 and a drawer 40. The retaining plate 39 is formed from a single blank of sheet metal, the longitudinal margins of which are upturned to provide the parallel side walls 41 and 42. The bottom wall 43 of the member 39 is, however, flat and unobstructed. On the forward edges of the side walls 41 and 42 are formed catch members 44 which extend inwardly toward the opposite ends thereof in parallel spaced relation to the said walls. The retaining plate 39 is mounted within one of the drawer receiving compartments of a cabinet in the manner of an ordinary drawer, but since the cabinet and its drawer receiving compartments does not form any part of the present invention and may be constructed along any standard lines, it has not been illustrated.

The drawer 40 is formed from a single sheet of metal and includes a bottom wall 45, parallel side walls 46 and 47 and end walls 48 and 49. The hinge member employed in pivotingly connecting the drawer 40 to the retaining plate 39 so that the drawer will be capable of swinging as well as sliding movement with respect to the plate consists in a single length of wire which is bent to produce a substantially U-shaped body portion 50. The terminals of the arms 51 of the member 50 are bent at right angles to produce the portions 52 which extend parallel to the bight of the U-portion 50. The U-shaped member 50 and the extensions 52 all lie in the same plane. The terminals of the extensions 52 are, however, bent at right angles, producing the catch fingers 53 which lie in a plane intersecting the plane of the members 50 and 52 at right angles. Adjacent the side walls 46 and 47 there are formed in the bottom wall 45 and at the rear terminal thereof, two slots indicated at 54 and 55. Communicating with these slots there are formed, in the lower edge of the end wall 49, the recesses or openings 56 and

57 which are adapted to receive the arms 51 of the U-shaped portion 50 when the drawer is in closed position within the retaining plate 39. It is of course necessary to pivotally attach the bight of the U-shaped portion 50 to the bottom wall 45. For this purpose, therefore, I provide hinge leaves 58. These hinge leaves 58 are formed by releasing portions of the metal of the bottom wall 10 as shown particularly in Fig. 4 and by bending these released portions of metal about the hinge rod.

It is now to be noted that the extensions 52 are of such length that the catch fingers 15 53 may be swung to a position along the outer faces of the side walls 46 and 47. The purpose in thus disposing the catch fingers 53 will be obvious, reference being had particularly to Fig. 5, in which figure, it will 20 be noted that the catch fingers are adapted to engage against the inner faces of the side walls 41 and 42 of the plate 39 and are designed to engage with the catches 44 when the drawer has been pulled from the retaining plate. When the catch fingers 53 are 25 engaged with the members 44, it is obvious that the arms 51 and extensions 52 will bear against the bottom wall 43 of the retaining plate, thus serving to hold the bight portion 30 of the member 50 in relatively fixed position so that the drawer 40 will be swung on the member 50 into depending position for enabling the user of the cabinet to readily remove or insert sale slips. It will be observed 35 that the U-shaped body portion 50 with its arms 51 of the hinge member for the drawer, constitutes a crank and that the fingers 53 of the said hinge member are adapted to engage the catches of the retaining member 40 for holding the said crank from turning 40 movement about its axis so that the crank will properly support the drawer in depending position when withdrawn from the retaining member.

45 The modified form of my invention, as shown in Fig. 6, includes, as do the other two forms of the device, a retaining plate 59 and a drawer 60. The member 59 is similar to the member 39 of Fig. 4, while 50 the member 60 is substantially similar to the number 40, except that the rear terminals of the bottom wall 61 is provided with a relatively large opening 62. This opening 62 receives the leg 63 of a substantially 55 L-shaped plate 64. The terminal of the member 63 is provided with the hinge leaves or tubular members 65 through which passes a hinge rod 67. Portions of the bottom wall 61 are released in the manner hereinbefore 60 explained in connection with the members 58 of Fig. 4 for the purpose of properly attaching the hinge rod to the bottom wall. To the leg 68 of the plate 64 is secured a bar 69 which is of a length equal to the distance 65 between the side walls of the retaining plate

59. It will be readily appreciated, when reference is had to Fig. 6, that when it is desired to dispose the drawer within the retaining plate, the end wall 70 of the drawer may be swung to engage against the member 69. It will also be noted that when the drawer is withdrawn from the plate 59, the terminals of the bar 69 will engage with the catch members 71 of the retaining plate side walls. When the terminals of the bars 69 are thus engaged, the portion 63 of the plate 64 will be relatively fixed upon the bottom wall of the member 59 and as a result, the plate 64 will form a pivotal support for the drawer 60 so that this member may be 75 readily swung downwardly on the rod 67 and arranged in dependent position.

In reduction to practice, it has been found that the form of this invention illustrated in the drawings, and referred to in the above 80 description as the preferred embodiment, is the most efficient and practical; yet realizing that the conditions concurrent with the adoption of this device will necessarily vary, it is desired to emphasize the fact that 85 various minor changes in details of construction, proportion and arrangement of parts may be resorted to, when required, without sacrificing any of the advantages 90 of this invention, as defined in the appended 95 claims.

Having thus described the invention, what is claimed as new is:

1. A drawer of the character described including a retaining plate having parallel side walls provided terminally with catch members, a drawer body slidable over the retaining plate, a catch member pivotally attached to the drawer body, said catch member consisting of a single length of wire bent intermediate its length to produce a substantially U-shaped conformation and having right angularly extending terminal portions adapted to engage between the fixed catch members and the side walls of the retaining plate when the drawer is withdrawn therefrom.

2. A drawer of the character described including a retaining plate having parallel side walls provided terminally with catch members, a drawer body slidable over the retaining plate, a catch member pivotally attached to the drawer body, said catch member consisting of a single length of wire bent intermediate its length to produce a substantially U-shaped conformation and having right angularly extending terminal portions adapted to engage between the fixed catch members and the side walls of the retaining plate when the drawer is withdrawn therefrom, the engagement of the said terminal portions of the second mentioned catch with the fixed catches serving to hold the U-shaped portions of the second mentioned catch in relatively fixed position on the bot-

tom wall of the retaining plate, whereby the drawer body may be swung about the bight portion of the U-shaped member into dependent position.

- 5 3. A drawer of the character described including a retaining element having side walls reduced at their outer extremities and bent to form catch members extending between said walls, a drawer body, and a hinge member carried by the drawer body and provided with portions extending adjacent to the side walls and shiftable to engage said catch members.
- 10 4. A drawer of the character described including a retaining element provided with catch members, a drawer body and a substantially U-shaped hinge member having its bight portion connected to the drawer and provided with fingers extending laterally therefrom relative to the plane of the bight portion, the drawer being shiftable to engage the fingers with the said catch members with the drawer depending from the said bight portion.
- 15 5. A drawer of the character described including a retaining element provided with catch members, a drawer body notched to receive a hinge member, and a substantially U-shaped hinge member having its bight portion freely connected to the drawer body with the arms thereof extending through said notches and provided with fingers extending laterally therefrom relative to the plane of the bight portion and said arms, the

drawer being shiftable to engage the fingers 35 with said catch members.

6. A drawer of the character described including a retaining element provided with catch members, a drawer body, and a crank member connected by its crank portion to 40 the drawer body and provided with upstanding fingers, the drawer being shiftable upon the retaining element to a position with the said fingers engaging the catch members for holding the crank from turning movement 45 about its axis and being movable about the said crank portion to depend therefrom.

7. A drawer of the character described including a retaining element provided with catch members projecting inwardly from the 50 sides thereof, a drawer body, and a hinge member provided intermediate its ends with a crank connected to the drawer, the hinge member having fingers formed thereon and the drawer being shiftable upon the retaining element to engage the fingers with the 55 catch members for supporting the crank in position to extend laterally from the retaining element with the arms of the crank engaging the bottom wall of the retaining element and with the drawer depending from the said crank.

In testimony whereof I affix my signature in presence of two witnesses.
